UNITED STATES PATENT OFFICE.

MAX DÜNNEBIER AND ALFRED WINKLER, OF NEUWIED-ON-THE-RHINE, GERMANY.

APPARATUS FOR FEEDING BLANKS.

1,153,296.

Specification of Letters Patent. Patented Sept. 14, 1915.

Application filed July 2, 1914. Serial No. 848,655.

To all whom it may concern:

Be it known that we, MAX DÜNNEBIER and ALFRED WINKLER, citizens of the German Empire, both residing at Neuwied-on-the-Rhine, Germany, have invented certain new and useful Improvements in Apparatus for Feeding Blanks, of which the following is a specification.

This invention relates to apparatus for gumming envelop blanks and like postal wrappers. In gumming such blanks the most successful methods hitherto adopted have been those which remove the top blank from a pile, this top blank being in contact with the felt in the gumming slot of a fountain gummer. It has also been proposed to gum the bottom blank of a pile by means of a moving device, such as a roller, which was applied with gum from a container. When using a fountain gummer to gum the top blank of a pile, leakage of gum is apt to occur and such gum which leaks from the slot trickles down the sides of the blanks in the pile and may eventually interfere with the operation of the machine when the device is used in combination with an envelop folding machine. The moving devices for applying gum to the bottom blank are not always satisfactory. The object of the present invention is to enable the proper gumming and withdrawal of the bottom blank of a pile, the gum being applied by means of what is known as a "fountain gummer". A fountain gummer might be said to consist of a chamber containing gum, which is supplied under a desired head to a slot.

According to this invention the gumming device comprises a fountain gummer provided with a gumming slot in contact with the bottom of the lowermost blank of a pile, which is partially supported on the gummer, and partly on a moving device which periodically and temporarily liberates the lowermost blank to permit of its withdrawal.

More especially the device, according to the present invention, comprises a fountain gummer, substantially L-shaped, with its gumming slot in contact with the lowermost blank of a pile which rests on the horizontally projecting leg of the gummer, while the opposite corners of the pile rest on two oppositely rotating horizontal incut disks

which are arranged side by side and have 55 their peripheral edges spaced while a suction nozzle or equivalent mechanical removing device is adapted to operate on the lowermost blank in the space between the peripheral edges of the adjacent disks. 60

The invention will be more readily understood from the following description of one convenient form illustrated by way of example in the accompanying drawings.

In these drawings: Figure 1 is a vertical 65 sectional elevation showing the device applied at the feeding end of an envelop folding machine. Fig. 2 is a plan of the device shown in Fig. 1.

In carrying the invention into effect according to the form shown, somewhat diagrammatically, in the accompanying drawings, the pile of blanks *a* is supported as regards its left hand edge in Fig. 1 on the horizontally projecting portion *f* of a fountain gummer *g*. The fountain gummer *g* is provided with a slot *h* and a felt wiper in the known manner. One ledge of the slot is higher than the other and this higher ledge receives the tips so that after receiving gum 80 from the felt this gum is not scraped off by the rear ledge. For the purpose of closing the slot when no blanks are resting on the gummer, a valve *d* supported on an arm *e* which is held upward by a spring *i* may be 85 provided. The opposite end or edges of the blanks are supported by moving members consisting, in the form shown of disks *b*, *b*. These disks are arranged side by side in a horizontal plane and their peripheral edges 90 are spaced apart symmetrically in regard to the center line X-Y of the blanks. This center line is also the center line of movement of the blanks when they are removed from the pile. The disks *b* are arranged to 95 project only for a short distance under the edges of the blanks. The pile of blanks is thus supported at three points, namely, on the gummer and on the two moving disks.

The moving disks are arranged to liberate 100 periodically and temporarily the lowermost blank of the pile, so as to permit its withdrawal. For this purpose the disks are provided with incut portions *c* of substantially triangular form. The portions *c* are adapted to come opposite one another in the manner shown in Fig. 2, just at the time when the suction nozzle *k*, moves up into contact

with the lowermost blank and starts its downward motion again. The disks *b* rotate in opposite directions indicated by the arrows *j*. If now the nozzle *k* has deflected the blank downward as shown in Fig. 1, the edge *b'* of the incuts or slots *c* constitutes the line of flex of the blank. This line of flexing recedes rearwardly as the disks rotate. At the same time the edge *b²* moves 10 under the pile between the flexed blank and the rest of the pile. When the edge *b'* has moved away out of contact with the bottom of the pile, the bottom blank is free to be moved downward and away from the pile. 15 This movement draws the blank over the gum slot *h* whereby an even uniform coating of gum is applied to the blank. This gummed edge does not in any way come in contact with the disks *b* so that there is no 20 danger of these disks becoming smeared or doing any damage to the blanks. The nozzle *k* flexes the blank downward until the segmental overhanging edges *m'* of rollers *m* take up the further flexing of the blank, 25 and start its forward feeding. The rollers *m*, *m* are supported on either side of the center line X—Y on separate spindles, the space between the adjacent faces of the rollers being occupied by the moving nozzle *k*. 30 The overhanging segmental edges *m'* are formed by recessing the ends of the rollers *m* and cutting away portions of the rings so formed. The gap in the overhanging edges *m'* is opposite the feed roll *n* when the blank 35 is in the flexed position shown in Fig. 1, and is about to be liberated by the nozzle *k*. The rollers *m* are supported on spindles *o* which also support the rollers *p*. The spindles *o* are mounted on swinging arms *q*. 40 Springs *r* tend to pull the arms *q* to the left hand in Fig. 1 and consequently retain the rollers *m* and *p* in contact with the feed roll *n*. The feed roll *n* is provided with a gap

or recessed portion where it comes opposite the gummed portion of the blank.

45

Any suitable means may be employed for driving or moving the parts mentioned. The nozzle *k* may be mounted on an arm *s* pivoted at *t* and caused to swing by means of a cam *u* mounted on the axis of the roller *n*. The rollers *m* and *p* may be rotated by their contact with the feed roll *n*. The disks *b* are mounted on vertical axes which are rotated by bevel gearing *v*. The blanks gummed and fed as above described are led 50 through the tapes *w* to the folding mechanism *z*. An arcuate guide *k'* may be provided to retain the blank flexed and guide it into the tapes *w*.

55

We claim:

1. Blank feeding mechanism comprising apertured rotary members, a support for a pile of blanks which also rest partially on said rotary members, a suction nozzle movable past said members to draw down the 65 lowest blank through said apertures, means for flexing said blank away from said nozzle and means for further transporting the blank away from the pile.

2. In combination a support for a pile of 70 blanks oppositely rotating apertured disks, a suction nozzle movable past said disks to flex the lowermost blank from the pile, rollers supported laterally of said nozzle, overhanging segmented edges on said rollers 75 said edges being located to engage the blank and separate it from the nozzle.

In testimony whereof we have signed our names to this specification in the presence of two subscribing witnesses.

MAX DÜNNEBIER.
ALFRED WINKLER.
